DRAWER HANDLE OR SIMILAR ARTICLE

Pehr J. Anderson, St. Charles, Ill., assignor to All-Steel Equipment Inc., Aurora, Ill., a corporation of Illinois

Filed July 5, 1960, Ser. No. 61,238

Term of patent 14 years

(Cl. D10—8)

Fig. 1.

Fig. 2. 5+

Fig. 3.

Fig. 5.

FIGURE 1 is a front perspective view on a reduced scale of a drawer handle or similar article, showing my new design;

FIGURE 2 is a top plan view thereof;

FIGURE 3 is a rear elevational view thereof;

FIGURE 4 is a bottom plan view thereof; and

FIGURE 5 is a sectional view taken along the line 5—5 of FIGURE 2.

The characteristic features of my design for the handle disclosed reside in the gradual taper downwardly from front to rear of the top face of the handle, the beveled front face, and the horizontal bottom face which blends

into a relatively steeply inclined rear face, as best shown in FIGS. 3 and 5.

I claim:

The ornamental design for a drawer handle or similar article, substantially as shown and described.
